UNITED STATES PATENT OFFICE.

GEORGE W. BROWN, OF CAPE ELIZABETH, MAINE.

MATCH-LIGHTER FOR FLUID-BURNING APPARATUS.

1,325,462.

Specification of Letters Patent. Patented Dec. 16, 1919.

Application filed October 21, 1918. Serial No. 258,969.

To all whom it may concern:

Be it known that I, GEORGE W. BROWN, a citizen of the United States, residing at Cape Elizabeth, in the county of Cumberland and State of Maine, have invented certain new and useful Improvements in Match-Lighters for Fluid-Burning Apparatus, of which the following is a specification.

10 This invention relates to improvements in fluid burning apparatus and more especially to lanterns and lamps which are used in the open air. It relates specially to means for conveniently lighting the apparatus in the 15 open air, and closing the opening through which the match is introduced to the burner to exclude the air and wind when lighted. For convenience, I have shown my invention applied to a lantern having an oil burner, 20 but it may be applied in many cases to lamps and to gas burners.

In the drawings herewith accompanying and making a part of this application, Figure 1 is an elevation of a lantern showing 25 my improvements applied thereto: Fig. 2 is a detail sectional view, partly in elevation, of the same: Fig. 3 is a detail plan view of the same, the globe, cage and top being removed: Fig. 4 is a detail elevation of the 30 same: Fig. 5 is a detail view of a modified form of my invention: Fig. 6 is a detail sectional view of the same, and Fig. 7 is a plan view of a blank from which the guide shown in Fig. 2 may be made.

35 The same reference characters indicate like parts in the several figures.

In said drawings, 1 is a base, 2 a tank-holding case, 3 a tank, 4 a wick tube, 5 a wick, 6 a globe cage, 7 a globe, 8 a perforated cupola and 9 a handle. These parts 40 may be of any style and convenient construction and alone form no part of my invention.

Various attempts have been made to construct devices with means for accomplishing the results aimed at, but so far as applicant is aware, none have been produced which have been very satisfactory or which have come into general use, although the 45 want is real and means for supplying the want have been sought for a long time.

Applicant has conceived the idea of providing a somewhat extended scarifying surface secured to or supported by the tank or 50 casing below the top of the burner tube, and terminating at a point adjacent the receiv-

ing end of a guide leading to a point at or near the top of the burner tube. Applicant has found it of the greatest importance that there may be a somewhat extended scarifying 60 surface so that a quick movement of the match thereover will serve to ignite it and so arranged that, when ignited, it may be in position to be directly guided to the burner tube inside the globe. Having these 65 necessary conditions in view, reference will now be made to the accompanying drawings.

In Figs. 1, 2, 3 and 4, a scarifier 10 is applied in any convenient manner to the outside wall of the tank and the casing is 70 provided with a slit or opening 11 arranged to register with the scarifier. Above the top of the scarifier is a match guide 12, its upper end terminating at a point adjacent the burner tube. The scarifier, match guide, 75 and opening in the casing are so positioned that a match inserted through the opening and moved in contact with the scarifying surface is lighted and the continued movement of the lighted match controlled by the 80 guide impels the ignited match into position to light the device. The guide may be supported in any convenient manner. As shown in Figs. 1 to 4, it is supported upon the burner tube and may be formed from 85 a blank such as is shown in Fig. 7, formed by bending the intermediate part 13 around the burner tube and bringing the ends 14 together in an inclined position relative to the scarifier thus forming an open guide 90 way or trough. To prevent the air passing through the slit to the flame, I provide a slide 15 which may be moved over and close the slit after the device is lighted. For convenience, the casing adjacent the slit is provided 95 with a recess adapted to receive a knob 16 on the slide.

In Figs. 5 and 6, I have shown a modified arrangement of my device. In this case, the scarifier is removably mounted in a tube 17 100 attached to the casing. Secured in any convenient manner to the top of the scarifier and carried thereby is a match guide terminating adjacent the wick as before. The casing adjacent the scarifier is likewise provided with a slit which is adapted to be closed by a vertically movable slide 18. The slide, when raised, is free to move laterally to enable the knob to pass into the recess 105 casing and hold it up.

110 It is to be noted that any arrangement which embraces an exposed scarifying sur-

face leading to a match guide and so arranged that a match can be applied thereto with a quick movement and continued, after being ignited, through a match guide to the 5 burner is within the spirit and scope of my invention.

It is also to be noted that the match guide may be omitted when the distance from the scarifier to the burner tube is so short as to 10 render a special guide for the match unnecessary.

I claim:

1. In a device of the character described, the combination with a fluid burner, a 15 burner chamber and a supporting case provided with a substantially vertically extending slit, of an extended scarifier mounted in said slit, whereby a match may be passed quickly over the scarifier and thence in a 20 substantially vertical direction on to the burner.

2. In a device of the character described, the combination with a fluid burner, a burner chamber and a supporting case provided with a substantially vertically extending slit terminating in an opening lead-

ing into said chamber, of an extended scarifier mounted in said slit, whereby a match may be passed quickly over the scarifier and thence in a substantially vertical direction 30 on to the burner and means for closing said opening.

3. In a device of the character described, the combination with a fluid burner, a burner chamber and a supporting case provided with a slit therein, a match guide leading from said scarifier to said burner, of a scarifier mounted in said slit, the receiving end of the match guide being positioned to receive the match as it passes in a substantially vertical direction from the scarifier. 35

4. In a device of the character described, the combination with a fluid burner, a burner chamber and supporting case provided with a vertically extending slit terminating in an opening into said chamber, of a scarifier mounted in said slit and a match guide interposed between said scarifier and said burner and means for closing said opening into the chamber. 40

In testimony whereof I affix my signature. 45
GEORGE W. BROWN.
